UNITED STATES PATENT OFFICE.

WALTER A. RARIG, OF OAKLAND, CALIFORNIA.

OIL-CONDUCTING TERMINAL.

Application filed September 30, 1925. Serial No. 59,716.

The present invention relates to improvements in oil conducting terminals for automobiles, and is designed particularly to be used for the fly wheel casing of the Ford automobile. The general object of the device is to support a terminal for the magneto of the motor vehicle in combination with an oil catching device which latter allows the oil splashed by the fly wheel to be returned to the drip pan of the engine. Different forms of a combination oil catch and terminal have been described in my co-pending applications, Serial Number 663,792 and Serial Number 35,604.

The present invention shows a modified form in which the terminal and the oil catch are accommodated within a bushing adapted to be screwed into the top of the casing while a guide member for the oil surrounds the bushing and communicates with a tube leading the oil to its place of destination.

The preferred form of my invention is illustrated, in the accompanying drawing, in which:—

Figure 1 shows a vertical section through my device.

Figure 2 a top plan view of the same.

Figure 3 a top plan view of an oil guiding shell,

Figure 4 a detail view inside elevation of a bushing,

Figure 5 a detail view inside elevation of an oil catching member,

Figure 6 an end view of the latter.

While I have described only the preferred forms of the invention, I wish to have it understood that various changes or modifications may be made within the scope of the claims hereto attached without departing from the spirit of the invention.

The bushing 1 illustrated in detail in Figure 4 is threaded at its lower end as shown at 2, and is adapted to be screwed into the casing 3 of the fly wheel in a manner illustrated in Figure 1. A collar 4 preferably made angular allows a wrench to be used on the bushing, and a smooth surface between the collar 4 and the threaded portion 2 is adapted to receive a shell 6 which is clamped between the collar 4 and the top of the casing. The shell is provided with an annular groove 7 in the inner face thereof of which latter communicates with a tube 8 leading to the outside and preferably

threaded into an insert 9. The bushing is provided with a hole 11 communicating with the groove 7. Inside of the bushing 1, and extending throughout the length thereof there is accommodated an insulating sleeve 12 having a rather large bore 13 in its lower portion and a smaller bore 14 in its upper portion, and insert 16 in the upper portion allowing a terminal 17 to be screwed thereto in such a manner that the lower end 18 of the terminal is spaced from the lower portion of the insulating sleeve by a considerable distance. The terminal is provided at its bottom with a spring actuated contacting needle 19.

My oil catching member 21 is illustrated in detail in Figures 5 and 6 and consists of a sheet of bendable metal turned into cylindrical form with the two ends 22 and 23 slightly spaced. The tendency of this member is to spread so that when introduced into the insulating member 12 from the bottom it is held in position.

A scoop 24 secured at its lower end is arranged opposite the split 26 between the two ends 22 and 23 and extends below the bottom of the bushing. The scoop is preferably arranged so as to occupy a certain position relative to a mark 27 on the top of the bushing so that it may be properly positioned in the casing. The position may be such that it is only necessary to arrange the arrow in the direction of rotation of the fly wheel. If upon screwing down the bushing 1 it is found that the arrow 27 does not point in the direction of rotation of the fly wheel, a washer may be inserted between the shell 6 and the casing to alter the position of the arrow 27. To insure correct positioning of the scoop 24 it may be formed with a recess 28 adapted to register with the hole 11 in the bushing 1.

The assembly of the device is easily understood from the foregoing description: the insulating member 12 is pushed into the bushing in a manner illustrated in Figure 1 and the catch member 21 is pushed into the insulating member from the opposite side in such a manner that the recess 28 registered with the perforation 11 in the bushing 1 and a registering perforation in the insulating member. The terminal 17 may be threaded into the insulating member at any time. After interposing the shell 6 between the collar 4 of the bushing 1 and the top

of the casing, the bushing is then threaded into the casing and the position of the arrow 27 noted. If the arrow points in the direction of rotation of the fly wheel its position 5 is correct and if not, its position is changed by the insertion of one or more washers.

Having described my invention, I claim:—

1. An oil conducting terminal comprising 10 a sleeve having a flange at its upper end and being adapted to have its lower end threaded into a casing, a ring surrounding the sleeve adapted to be clamped between the casing and the flange and formed with an annular groove in the inner face thereof and with a lateral outlet for the same, and a hollow in-

sulating body within the sleeve having an axial terminal element supported therein.

2. An oil conducting terminal comprising 20 a sleeve having a flange at its upper end and being adapted to have its lower end threaded into a casing, a ring surrounding the sleeve adapted to be clamped between the casing and the flange and formed with an annular groove in the inner face thereof and with a lateral outlet for the same, a hollow insulating body within the sleeve having an axial terminal element supported therein, and a cylindrical element inside of the insulating body cut to form a scoop below the sleeve. 25 30

In testimony whereof I affix my signature.
WALTER A. RARIG.
